[57] CLAIM

The ornamental design for a support unit for cleaning and electroplating equipment or the like, as shown and described.

DESCRIPTION

The sole FIGURE is a front perspective view of a support unit for cleaning and electroplating equipment or the like showing my new design.

The rear and right side, which are not shown, are planar and unornamented except for the appearance of the hood which conforms to those sides shown. The top and bottom are also unornamented.
